COMBINATION WEATHER-STRIP AND
WINDOW FRAME

Hermann J. Schubert, Hackensack, N. J.

Application August 10, 1933, Serial No. 684,481

12 Claims. (Cl. 20—45)

My present invention relates to certain new and useful improvements in combination weather-stripping and window frames, where there is free opportunity to open the windows and 5 tilt the same inwardly without dismantling the weather-strips, and where the windows can be readily closed and the weather-strips restored to absolutely weather tight position as before. An object to be mentioned among many is to permit 10 the use of metal weather-strips which will act as cooperative guides as well as weather-stripping, and also by pivotally arranging the retaining strips or portions thereof in the window frames the window sashes may be swung inwardly for 15 cleaning purposes and then restored to normal position in a solid weather tight manner without the difficulty and expense of employing ordinary supplementary weather-stripping which is often complicated and expensive. And the invention 20 may therefore be said to consist essentially in the construction, combination, and arrangement of parts, substantially as will be hereinafter described and claimed.

In the accompanying drawings illustrating my 25 invention:

Figure 1 is a front elevation of a window frame built to embody the several features of my new 30 invention and shows the weather-stripping combined therewith, the window sashes being shown as closed.

Figure 2 is a vertical section of the same on the line 2, 2, of Figure 1.

Figure 3 is a similar vertical section, showing 35 the window as open with its pivoted strips and sashes tilted inwardly.

Figure 4 is a cross-section on the line 4, 4, of 40 Figure 2.

Figure 5 is a cross-section on the line 5, 5, of 45 Figure 2.

Figure 6 is a sectional partial plan broken away and taken on the line 6, 6, of Figure 3.

Figure 7 is an enlarged detail view of the upper 50 ends of the strips on the inner sash and inner retaining strip.

Similar characters of reference designate corresponding parts in all the different figures of the drawings.

1 denotes an ordinary rectangular window frame of the conventional type, having the vertical inner opposing channels 2 and 3 on each side for the window sashes 4 and 5, said channels being thus divided into the two usual guideways for the two sashes 4 and 5 by means of the outer retaining strip 8, the inner retaining strip 6 and 55 6^a, and the middle parting strip 7 and 7^a. Any or

all of these retaining and guiding strips may be made integral with the frame 1, or they may be made separate and detachable, both channels 2 and 3 on the opposite sides of the frame being made in the same manner. In the present example of the invention the middle parting strip is made of two parts 7 and 7^a, the meeting or adjoining ends of strips 7 and 7^a being beveled or chamfered at 7^b where they engage each other near the middle of the vertical length of channels 2 and 3. The upper pieces 7 are secured rigidly in channels 2 and 3, while the lower pieces 7^a are loose and pivoted at their lower ends at 7^c in the lower ends of channels 2 and 3, so that they may occupy a position in vertical alignment with parts 7, as shown in Figure 2, and at other times may be tilted downwardly and inwardly, as in Figure 3. The same bisectional construction is true of the inner retaining strip which consists of two pieces 6 and 6^a, the pieces 6 being fast in 10 the frame and pieces 6^a being hinged at their lower ends at 6^c. The adjoining meeting ends of strips 6 and 6^a are beveled at 6^b. Thus pieces 6^a may occupy the vertical or the tilted positions. And they function with the sash 5, as the strips 15 7^a function with the sash 4, as shown in Figure 3.

To the sashes 4 and 5 metal bars 9 and 10 are pivoted at 9^c and 10^c. Chains 9^a and 10^a are fastened to the bars 9 and 10, and these chains also connect with the sash weights 9^b and 10^b, 20 said chains running over pulleys in the upper end of frame and supporting the weights in the usual receptacles in the frame, as shown in Figure 3. These window sashes 4 and 5 both have a rounded portion 4^a and 5^a, usually small, see Figure 6, 25 30 at their lower ends to enable the windows to more easily swing inwardly, as shown in Figure 3, these round places being at each end of the sash.

To the opposite vertical edges of the outer or top window sash 4 are secured by screws or otherwise angular or L-shaped metal guides 17, or which the bent angular part 17^a straddles or encloses the dividing strips 7 and 7^a, and as the sash 4 is raised or lowered the guides 17 on 40 45 the respective edges of the sashes 4 ride up and down on these dividing strips. The way the guides 17 engage strips 7 and 7^a is brought out clearly in Figure 4.

On the opposing vertical edges of the lower or inner sash 5 are secured by screws or otherwise a metal strip 16, having a portion along one of its longitudinal edges bent over on itself at 16^a to thicken a part of the plate and form a guide for the flange 15^b of the right angled metal strip 50 55 55

15, the angular member 15^a of which is secured to the pivoted inner retaining strips 6^a. These parts are clearly portrayed in Figures 4, 5, and 7. The strip 15^b is received into the guide formed 5 by the strip 16 on the sash 5. Thus the strips 15 and 16, one on the sash and the other on the inner strip 6^a are interengaged, and strip 16 slides on strip 15 which is within its guide as sash 5 is raised and lowered. At the upper end 10 of flange 15^b of strip 15 is a slot 15^c which cooperates with a pin 16^b on the metal strip 16. Said slot and pin connection is for the purpose of enabling the side strips 6^a and the window sash 5 to be held more securely together when they 15 are swung inwardly as shown in Figure 3 for the purpose of easy access for cleaning and other purposes, for it will be seen that when the strips 6^a and the sash 5 are alongside of each other, the sash 5 being down in the closed window position, 20 the flange 15^b engages behind the strip 16 and the slot 15^c receives and engages pin 16^b to hold the parts together when the strips 6^a turn on their pivot pins 6^c.

On each strip 6 is mounted a locking device 25 consisting of a slide 11 having a handle 14. The slide 11 is held by screws 12 that work in a slot 13, and by laying hold of the thumb pieces 14 the slides 11 can be moved up and down. When they are pushed down below the position shown in 30 Figure 3 into the lower position shown in Figure 1 they will embrace the joints at 6^b where the ends of strips 6 and 6^a are in contact, so that the strips 6^a are locked to strips 6 and cannot be let down into the position shown in Figure 3. When 35 the locks 11 are raised into the position in Figure 3, they are released from the strips 6^a and they can be swung down on their pivots at 6^c into the lowered position in Figure 3, carrying with them the sash 5, which will then be in position for 40 cleaning or such other attention as it may need.

It will thus be understood that the metal strips 17, 15, and 16, arranged in the way I have described constitute effective weather stripping which are closely and tightly fitted to keep out 45 cold air and storm. But the use of these tight pieces does not interfere with the movement of the windows when they require to be tilted or swing inwardly for cleaning and other purposes. The windows can be opened or closed at any time, 50 and tilted at any time, and yet the weather-strips are not disturbed in such a way as to impair their efficiency or value.

The operation and use will be clearly understood from the foregoing description of the construction and application of the different parts. 55 Many changes in the arrangement and combination may be made within the terms of the claims without departing from the invention and I reserve the liberty of readjusting the parts to meet the requirements of individual cases. My improved device can be easily applied to existing window frames by dividing the middle and inner retaining strips at or near the center with angular cuts and substituting pivoted strips instead of the lower half of each inner strip.

What I claim is:

1. In a mechanism of the class described, the combination with window sashes and a frame having channels in which the sashes slide, of strips on the sides of the channels, some of which are stationary and others of which have stationary and movable sections, an angular weather-strip on one sash engaging and slidable on one of the two-part strips, and an angular weather-strip on the other sash, together with an angular

strip on the other two-part strip engaged by the aforesaid angular strip on the other sash, and means for locking together the two parts of the latter strip, comprising a pin on one strip entering a slot in the other.

2. In a window frame and weather-strip combined, the combination with a sash, of a window frame having channels, retaining strips forming said channels, of which some are in half sections whose meeting edges are inclined, the upper half section being stationary and the lower half section being pivoted at the lower end, sliding locking means for holding the sections of the inner retaining strip in alignment with each other at times, weather-stripping on the lower sash and means on the sectional retaining strip for engaging said weather-stripping means to make a tight joint when the window is closed and to permit the joint tilting of sash and sectional strip when the window is open.

3. In a device of the class described, a channeled window frame, a sash slidable therein, a retaining strip for the sash in the channels of the window frame, a weather-strip on the sash, a cooperating weather-strip on the retaining strip, said retaining strip being in two parts, one of which is stationary and one of which is hung to swing, a lock to keep the two parts of the strip aligned with each other at times, and means for enabling the movable portion of the retaining strip to carry the sash when it swings, consisting of interengaging angular pieces and a lock comprising a pin in one piece entering a slot in the other piece, and counterbalancing means for the sash including a bar pivoted to the sash, a weight in the frame, and a flexible line connecting the weight and bar.

4. In a mechanism of the class described, the combination with a frame having channels for the sliding sashes and retaining strips for said sashes, the outer being stationary and the middle and inner being each in two parts, the lower of which are pivoted at the lower end to swing inwardly, and weather-stripping means for connecting the sashes to the movable strips so that they may be swung inwardly, therewith when the sashes are in their lower positions, comprising angular strips secured to the upper sash and engaging the middle parting strip, and angular strips on the lower sash interengaging with angular strips on the pivoted portions of the inner retaining strips, together with counterbalancing means for the sashes including weights and flexible connections between them and the sashes.

5. In a mechanism of the class described, the combination with a frame having channels for the sliding sashes and retaining strips for said sashes, the outer strips being stationary, and the middle and inner being divided into two parts, the lower of which are pivoted at the lower end to swing inwardly, an angular strip on the top sash, loosely engaging the middle retaining strip and tilting with the pivoted part thereof when it tilts, an angular strip on the lower sash bent to form a channel, another angular strip on the pivoted portion of the inner strip which engages said channel and enables the lower sash and the pivoted portion of the inner strip to tilt in unison, said angular strips being effective as weather-strips as well as means for connecting the sashes with the movable strips, and counterbalancing means for the sashes to hold them in balanced relation when tilted as well as when being raised and lowered.

6. In a mechanism of the class described, the

combination with sliding sashes and a window frame having channels for the sashes, said channels being formed with retaining and dividing strips, some of which are in two parts, of which 5 the lower portion is pivoted and the upper is stationary, and weather-strips consisting of angular pieces secured to the sashes, that secured to the upper sash loosely embracing and sliding on the middle retaining strip, and the angular weather- 10 strip on the lower sash being engaged by an angular piece on the inner retaining strip, so that the pivoted portions of the retaining strip and the sashes may be interlocked when the sashes are swung inwardly to make the sashes 15 accessible for various purposes, means for locking the parts of the inner strip together at times, and counterbalancing means for the sashes, comprising bars pivoted to the sashes, counterweights arranged in the frame, and connecting lines be- 20 tween the weights and bars.

7. In a device of the class described, the combination with a window frame having channels for the sliding sashes and retaining strips for said sashes, the outer being stationary and the 25 middle and inner being each in two parts having beveled meeting ends, the lower of which parts are pivoted at the lower end to swing inwardly, sliding locking means for holding the sections of the inner retaining strips in alignment with each other at times, angular strips secured on the top sash loosely engaging and sliding on the middle retaining strip and tilting with the pivoted part thereof when it tilts, an angular strip on the lower sash forming a channel thereon, another angular strip on the pivoted portion of the inner retaining strip and engaging the aforesaid channel so that the lower sash and pivoted portion of the inner strip tilt together, and counterbalancing means for the 30 sashes to hold them in balanced relation when tilted as also when being raised or lowered.

8. In a mechanism of the class described, the combination with a frame having channels for the sliding sashes and retaining strips for said sashes, the outer being stationary and the middle and inner being each of two parts, the lower of which are pivoted at the lower end to swing inwardly, and means for connecting the sashes to the movable strips so that they may be swung 45 inwardly therewith when the sashes are in their lower positions, comprising angular strips secured to the upper sash and engaging the middle parting strip, and angular strips on the lower sash interengaging with angular strips on the pivoted portions of the inner retaining strips, all arranged to cooperate as described.

9. In a mechanism of the class described, the combination with a frame having channels for the sliding sashes and retaining strips for said sashes, the outer strips being stationary, and the middle and inner being divided into two parts, the lower of which are pivoted at the lower end

to swing inwardly, an angular strip on the top sash loosely engaging the middle retaining strip and tilting with the pivoted part thereof when it tilts, an angular strip on the lower sash bent to form a channel, another angular strip on the pivoted portion of the inner strip which engages said channel and enables the lower sash and the pivoted portion of the inner strip to tilt in unison, and counterbalancing means for the sashes. 5

10. In a device of the class described, the combination with a window frame having channels for the sliding sashes and retaining strips for said sashes, the outer being stationary and the middle and inner being each in two parts having beveled meeting ends, the lower of which parts are pivoted at the lower end to swing inwardly, angular strips secured on the top sash loosely engaging and sliding on the middle retaining strip and tilting with the pivoted part thereof when it tilts, an angular strip on the lower sash forming a channel thereon, another angular strip on the pivoted portion of the inner retaining strip and engaging the aforesaid channel so that the lower sash and pivoted portion of the inner strip tilt together, and counterbalancing means for the 20 sashes. 15

11. In a mechanism of the class described, a sash mounted for vertical sliding and angular tilting movement, and suspending means therefor comprising a tension member connected to each side of the sash, counterbalancing weights adapted to maintain said members under tension, said members being attached to the sash at points intermediate the upper and lower extremities thereof whereby to maintain the sash in at least 30 a partially balanced condition in any angularly adjusted or vertical position. 35

12. In a mechanism of the class described, the combination with a frame having channels for the sliding sashes and retaining strips for said sashes, the outer being stationary and the middle and inner being each of two parts, the lower of which are pivoted at the lower end to swing inwardly, of means for connecting the sashes to the movable strips so that they may be swung 40 inwardly therewith when the sashes are in their lower position, and counterbalancing means for said sashes comprising suspension members operatively interposed between said sash and frame, said suspension members being connected at 45 opposite sides of said sash in such manner as to permit the tilting as well as the raising and lowering thereof, the said members being connected to the sash at points intermediate the upper and lower extremities thereof whereby when the sash is inclined from the vertical the portions above and below the said points of connection will exert a partial balancing effect one upon the other, and means adapted to maintain said members under tension regardless of the position of the 50 sash. 55

HERMANN J. SCHUBERT
